CLAIM

The ornamental design for a multi-spout pouring device, as shown and described.

DESCRIPTION

FIG. 1 is a front elevational view of the multi-spout pouring device of the present invention; the rear view being a mirror image thereof;

FIG. 2 is a left side elevational view of the multi-spout pouring device of FIG. 1;

FIG. 3 is a right side elevational view of the multi-spout pouring device of FIG. 1;

FIG. 4 is a top plan view of the multi-spout pouring device of FIG. 1;

FIG. 5 is a bottom plan view of the multi-spout pouring device of FIG. 1; and,

FIG. 6 is a cross-sectional view of FIG. 1 taken along line 6—6.
